ATTORNEYS.

UNITED STATES PATENT OFFICE.

WILLIAM B. McDONALD, OF LAWRENCE, KANSAS.

COMBINATION WOOD AND CEMENT POST.

1,379,029.

Specification of Letters Patent. Patented May 24, 1921.

Application filed March 1, 1920. Serial No. 362,212.

To all whom it may concern:

Be it known that I, WILLIAM B. McDONALD, a citizen of the United States, residing at Lawrence, in the county of Douglas 5 and State of Kansas, have invented certain new and useful Improvements in Combination Wood and Cement Posts, of which the following is a specification.

My invention relates to improvements in 10 combination wood and concrete posts and may be used to advantage as a fence post, a telegraph post, a building post, etc.

Broadly speaking the invention consists of a wooden post and a concrete base to support said post above the ground so that it 15 will not rot out readily. The invention also embodies novel means for securing the post to the concrete block or foundation as the case may be.

20 In order that the invention may be fully understood, reference will now be had to the accompanying drawing, in which:

Figure 1 shows the device as a fence post.

Fig. 2 is a horizontal section on line 25 II—II of Fig. 1.

Fig. 3 shows the device adapted to either building purposes or as a corner post for fences.

Fig. 4 shows the device as a porch post.

30 Fig. 5 shows the device as a telegraph post.

Fig. 6 is a longitudinal sectional view of a fastening device employed in connecting the wooden post and the cement block 35 together.

Referring now more particularly to the device disclosed by Figs. 1 and 2, 4 designates a concrete block having an upward projection 6 to raise the base of the wooden 40 post 8 above the surface of the ground. The projection 6 is reinforced with one or more wires 10, arranged in rectangular form, and hooks 12 which engage the wires 10 and extend downwardly through the 45 block 4.

14 designates a tubular fastening device embedded centrally in the concrete block 4. The upper end of said tubular device 14 is, preferably, disposed flush with the top 50 of the projection 6, while its enlarged intermediate portion 16 is internally threaded to receive a screw 18 threaded or otherwise secured in the lower end of the post 8. The tubular device 14 not only provides means 55 for receiving the lower threaded end of the screw 18, but it also reinforces and pre-

vents the concrete from crumbling around the opening into which said screw 18 extends. The lower portion 20 of the tubular device 14 provides a space into which the 60 lower end of the screw 18 may project without contacting the concrete block 4 when the post 8 is screwed into position upon the projection 6.

The tubular device 14 and the screw 18 65 are assisted in holding the post 4 in upright position by means of braces 22 connected at their upper ends to staples 24 driven into the post 8 and connected at their lower ends to hooks 26 embedded in the concrete block 70 4. The wires 10 and 22 and the hooks 12, for the sake of economy may be made of old fence wire of which there is a plentiful supply on most farms. The concrete block 4 is provided with a hook 28 similar to 75 the hooks 26, for holding down the lower margin of a woven wire fence (not shown) when the same is applied to the posts. The concrete block 4 is also equipped with one or more wooden plugs 30, so that should the 80 upper portions of the hooks 26 and 28 rust off or become broken, holes are provided for additional hooks by removing the plugs 30, if the same have not already rotted out. When new hooks are placed in the 85 holes left by the plugs 30, they are fixed in place by pouring in cement, which on setting, firmly holds the hooks in place.

In the corner post 8^a disclosed by Fig. 3, the wire braces 22 are dispensed with 90 and one or more rigid braces 22^a are employed to hold said post 8^a in upright position. The upper end of the brace 22^a is secured to the post by a screw 32, while the lower end of said brace is secured by a 95 bolt 34 embedded in the block 4^a and provided with a nut 36. The lower end of the post 8^a is secured in place by an L-shaped anchor 18^a, the lower end of which is embedded in the concrete block 4^a, while its 100 upper portion is secured to the post 8^a by screws 38. Posts 8^a may be used to advantage in the construction of fences and barns or other buildings.

In the building post disclosed by Fig. 4, 105 the wooden post 8^b is held upon the concrete block 4^b by the projection 6^b, a pin 40 and a hook 42, the lower portion of which latter is embedded in said block 4^b.

In the form disclosed by Fig. 5, the 110 wooden post 8^c may answer as a telephone or telegraph post and is provided with a

clamp 44. Wire braces 22^e are secured at their upper ends to the clamp 44 and extend down to hooks 26^e secured in the concrete block 4^e. The braces 22^e are assisted in holding the post 8^e in upright position by anchors 18^e. If preferred rigid braces 22^a may be substituted for the wire braces 22^e.

Having thus described my invention, what I claim and desire to secure by Letters 10 Patent, is:

In a device of the character described, a concrete base provided at its upper side with a square projection, a threaded member embedded in said base, means to reinforce said

base, a post to fit upon the projection on 15 the base, a threaded member secured to the post and adapted to engage the threaded member on the base and secure the post in position, hooks embedded in the base, and braces connected to said hooks and the 20 post to secure the latter upon the former.

In testimony whereof I affix my signature, in the presence of two witnesses.

WILLIAM B. McDONALD.

Witnesses:

F. C. FISCHER,
L. J. FISCHER.
